FILLING THREAD CUTTER OPERATING
MECHANISMBenjamin W. Brouwer, Auburn, Mass., assignor
to Crompton & Knowles Loom Works, Worcester, Mass., a corporation of Massachusetts

Application December 27, 1948, Serial No. 67,439

6 Claims. (CL. 139—265)

1

This invention relates to controls for thread cutters more particularly adaptable for severing the thread of the outgoing bobbin in a weft replenishing loom and it is the general object of the invention to provide a simple form of control which can be set by a part of the replenishing mechanism to cause operation of the cutter.

When a bobbin changing operation occurs in the usual form of weft replenishing mechanism a thread extends from the shuttle eye along the front wall of the shuttle box to the selvage, and unless this thread is removed it may be drawn into the shed to form a thick place in the cloth. Various controls have been proposed heretofore for removing this thread, such as a pneumatic tube located between the shuttle and the cloth and acting to attract the thread before it has an opportunity to be whipped into the shed. With such removers it is customary to cut the thread near the eye of the shuttle, that part of the thread which remains attached to the exhausted bobbin being drawn out of the shuttle eye as the bobbin is expelled from the shuttle box, and the other part of the thread extending toward the cloth being drawn into the thread remover.

In order to effect cutting of this thread near the shuttle eye it has been proposed heretofore to use scissors type of cutters which may be mounted independently of the lay and move to cutting position under control of the transfer arm, or the cutter may be mounted on the lay and provision made to project the cutter blades rearwardly through or at least into a slot or cavity in the shuttle across which the thread extends as the lay approaches front center. The invention to be set forth herein relates more particularly to the latter type of cutter mechanism.

In multicolor weft replenishing mechanisms the magazine is set for a transferring operation by a shaft which rocks from its normal position to transfer position to move a shuttle positioner feeler rearwardly and also lift the latch of the transerrer arm. The shaft is rocked to transfer position before the lay reaches front center and then returns to normal position as the lay approaches front center. It is an important object of the present invention to provide means by which the operator mechanism for the thread cutter on the lay is controlled and positioned by connections with the rocker shaft. A lost motion connection permits the operator to remain in engagement with the cutter as the shaft returns to its normal position.

Multicolor weft replenishing magazines generally employ in their construction a stud serving

as a pivot for the transerrer arm and also tie rods which hold inner and outer bobbin guiding plates of the magazine. It is a further object of the invention to extend the transerrer arm supporting stud and preferably one of the tie rods to positions where they can support a carrier for the operator of the thread cutter.

With these and other objects in view which will appear as the description proceeds, the invention resides in the combination and arrangement of parts hereinafter described and set forth.

In the accompanying drawings, wherein a convenient embodiment of the invention is set forth:

Fig. 1 shows a front elevation of a multicolor weft replenishing mechanism of well-known type together with adjacent parts of the lay and shuttle box,

Fig. 2 is a diagrammatic view showing the manner in which the previously mentioned rocker shaft is moved from its normal position to transfer position,

Fig. 3 is an enlarged vertical section on line 3—3 of Fig. 1, and

Fig. 4 is a detailed enlarged vertical section on line 4—4 of Fig. 1 showing the operator for the thread cutter.

The present invention is shown as applied more particularly to a multicolor weft replenishing magazine M which has inner and outer bobbin guiding plates 10 and 11 held in spaced relation by means of the usual tie rods, two of which are shown herein at 12 and 13. The inner plate 10 is mounted on a support 14 fixed to the loom frame 15. The plate 10 supports a top rocker shaft 16 and also a color slide designated generally at 17. Vertical bobbin releasers are mounted on the left side of the end plate 10 as viewed in Fig. 1 one of which is indicated at 18. A pair of vertically spaced fingers 19 and 20 on the releaser cooperate with the color slide to raise and lower it.

An arm 21 is secured to the rocker shaft 16 and is connected to the upper end of a depending rod 21a operatively connected to the shuttle position feeler 22 which may be of usual form. Ordinarily the shuttle feeler is in forward position clear of the path of the shuttle S as it moves along the lay 23 toward the shuttle box 24, but when the rocker shaft 16 turns in a clockwise direction as viewed in Fig. 1 from its normal position to transfer position the rod 21 rises and moves the shuttle feeler 22 rearwardly. If the shuttle is misplaced it engages the shuttle position feeler and moves it forwardly to effect return movement of the shaft 16 to its normal position and prevent

completion of or revoke the previously called re-plenishing operation.

The transferrer arm 25 has a hub 26 pivotally mounted on a stud 27 which may conveniently be fastened to a part of the inner bobbin guiding plate 10. The transferrer arm has a transferrer latch 28, normally down, under control of a vertical rod 29 the upper end of which is attached to an arm 30 secured to shaft 16. When the latter moves to transfer position rod 29 is depressed and the transferrer latch 28 is lifted to the transfer position to cause operation of the transferrer arm by the advancing lay.

The weft detector 31, its detector shaft 32, the controller or chopper pin 33, the actuator or chopper lever 34, and the upright rod 35 may all be of usual construction. The latter rod effects counter-clockwise rocking of the color slide 17 when the detector indicates weft exhaustion, thereby lifting one of the releasers 18 so that a dog 36 on the upper end thereof, see Fig. 2, will overhang a bar or shelf 37 secured to the shaft 16. At a later time in the loom operation the color slide will be rocked clockwise as viewed in Fig. 1, and return releaser 18 to its normal down position. During this return motion dog 36 engages the shelf 37 and rocks shaft 16 and parts carried thereby from normal to transfer position. The normal position of these parts is suggested in full lines and the transfer position thereof in full lines in Fig. 2.

The magazine is of common construction in multicolor weft replenishing looms and a further description is not thought necessary. It is believed sufficient to state that when a weft replenishing operation is initiated by the detector one of the slides 18 will rise, and when the depleted shuttle is about to return to the magazine end of the loom the previously raised bobbin releaser will descend to rock the rocker shaft 16 from its normal position to its transfer positions. If transfer occurs in normal manner the rocker shaft 16 will be returned to its normal position, as by engagement of the shuttle position detector 22 with a part on the lay, as the latter approaches front center. If transfer is revoked by a misplaced shuttle shaft 16 returns to its normal position at an earlier time in the loom cycle and while the lay is an appreciable distance behind front center.

As shown more particularly in Fig. 3, the shuttle box 24 is provided with a front wall 40 having a hole 41 therein which registers with a hole 42 in the shuttle S when the latter is properly boxed. The thread cutter mechanism C in the present instance is shown as being mounted on the box wall 40 and comprises a support 43 in which two scissors cutter blades 44 and 45 are slidably mounted. A pin 46 stationary on the support 43 passes through slots 47 and 48 in the cutters 44 and 45, respectively, so that when the latter are moved rearwardly they pivot about a stud 49 carried by a slide 50 mounted for back and forth motion on the support 43. Slide or carrier 50 is normally held forwardly in any approved manner, as for instance by a spring 51 shown in Fig. 1.

The thread cutter of itself forms no part of the present invention and may be made as set forth in prior patent to Beaverstock No. 1,265,590. The slide 50 will normally be in forward position with respect to the shuttle box, or to the right as shown in Fig. 3, but when it is moved rearwardly the cutter blades pass through the aligned holes

41 and 42 and sever the weft thread W of the outgoing bobbin B.

Except as noted hereinafter the matter thus far described is of common construction and forms no part of the present invention. The thread cutter will be located near the right end of the shuttle box as viewed in Fig. 1 so that it may cut the thread W at a point adjacent to the thread delivery eye (not shown) in the front wall of the shuttle.

In carrying the present invention into effect provision is made for pushing the slide or cutter blade carrier 50 rearwardly on weft replenishing beats of the loom. The lower tie rod 13, see Fig. 1, is extended as at 55 and the transferrer arm supporting stud 27 is also extended as at 56, so that both of these parts can have secured to them a support or plate 57. The latter, as shown in Fig. 3, has a slot 58 therein through which the extended end of the tie rod 13 projects and a set screw 59 in plate 57 engages tie rod extension 55 to fix the position of the upper left end of plate 57, see Fig. 3. Plate 57 is also fastened to the extended end 56 of the transferrer supporting stud 27 by set screw 60.

In order to provide additional support for the transferrer stud 27 at a point intermediate its ends a stand 61 may be provided secured at its lower end as at 62 to a part of the structure 63 which supports the weft detector and detector shaft 32. The upper end of the stand 61 is provided with a hub 64 through which the stud 27 extends and in which it is tightly held by set screw 65.

Projecting to the left of the plate 57 as shown in Fig. 1 is an arm 66 provided with a stud 67 having pivotally mounted thereon a lever 68 the upper end of which is provided with a stud 69 and the lower end of which is provided with a radial slot 70, see Fig. 4.

A connector or wire 71 has an elongated horizontal loop 72 thereon which defines a slot 73 into which extends the stud 69 on the upper end of lever 68. Rod 71 extends to the left from stud 69, see Fig. 1, and is attached as at 74 to an arm 75 secured to the rocker shaft 16 by a set screw 76.

The lower end of lever 68 is operatively connected to a sliding operator, designated generally at 77, for the thread cutter C. This operator has a hub 78 mounted for horizontal sliding on a preferably cylindrical stud or guide 79 parallel to transferrer stud 27 and the right end of which, Fig. 1, is secured to the plate or mounting 57 as at 80. The left end of guide 79 is secured as at 81 to a link 82 the upper end of which is secured as at 83 to the transferrer stud 27. The plate 57 and link 82 jointly serve as a mounting means for the guide 79, which need not necessarily be cylindrical. The cutter operator 77 has an arm 84 which extends diagonally upwardly and to the left, Fig. 3, and is provided with a V-shaped notch 85 which receives and is slideable along part of the transferrer stud 27 to prevent angular motion of the operator 77 around guide 79.

The lower part of the operator 77 has mounted thereon a spring plunger 86 which slides through a cylindrical shell 87 the foot 88 of which is secured in vertically adjusted position to the depending arm 89 of the operator by a bolt 90. The spring plunger comprises a rod 91 having a head 92 slidably in shell 87 and receiving the left hand thrust of a compression spring 93 in the shell, see Fig. 4. Nuts 94 at the forward end of

the rod 91 limit rearward movement of the head 92. Tapped into the head is a screw 95 which is adjustable longitudinally of the plunger and is held in adjusted position by a lock nut 96. The head 97 of the screw 95 is adapted for engagement with the cutter slide 50.

A torsion spring 98 is interposed between lever 68 and a collar 99 which is fastened as at 100 to the stud 67. The effect of this spring is to tend to hold lever 68 in the full line position shown in Fig. 1, that is, with the operator screw head 97 out of alignment or register with the slide 50 of the cutter.

During normal operation of the loom the lay will swing back and forth and as it approaches front center position the slide 50 of the thread cutter will traverse a path to the right of the operator plunger 86 as viewed in Fig. 1. When shaft 16 is rocked as already described from its normal position to its transfer position in order to set the magazine for transfer by lifting the latch 28 and rearward projection of the shuttle position feeler 22, arm 75 will move to the left, Fig. 1, and cause left hand movement of the connector 71 as viewed in Fig. 1. The right hand end of this connector by its engagement with the stud 69 will rock lever 68 in a counter-clockwise direction, Fig. 1, and in doing so will cause the operator 71 to slide to the right along stud or guide 79. The parts 68, 71, 77 and 75 will now be in the operating position shown in dotted lines, Fig. 1. Movement of these parts to operating position occurs while the lay is in a position behind front center. As the lay advances the plunger 86 being aligned or in register with the slide 50, engages the latter and moves it rearwardly with respect to the lay to effect cutting of the thread W. Compression spring 93 is stronger than the spring 51 and overpowers the latter during the cutting operation, but if by any circumstance some part of the cutter mechanism should be deranged and prevent rearward movement of the slide 50 with respect to the lay the spring 93 will compress to avoid breakage.

The cutter operation will be completed by the time the lay reaches front center, but by setting the screw 95 rearwardly cutting can be effected at an earlier point in the loom cycle, that is, before the lay reaches its front center position. If it be desired to effect earlier cutting the spring 93 may be compressed slightly as the lay reaches front center due to the fact that the slide 50 may have reached the limit of its rearward movement with respect to the lay before the latter is on front center.

The shaft 16 will ordinarily be returned to its normal position as the lay approaches front center and right hand movement of the arm 75 and connector 71 to their normal full line position, Fig. 1, may occur while the head 97 of screw 95 is still in engagement with the slide 50. The slot 73 is of sufficient length, however, so that the connector 71 can move from the dotted to the full line position shown in Fig. 1 without disturbing the stud 69 and lever 68, and the latter can remain in its dotted line position as shown in Fig. 1 so long as any considerable force is exerted between the slide 50 and the head 97 of screw 95. As the lay moves rearwardly the slide 50 will move away from the screw 95 and the spring 98 will rock lever 68 from its operating dotted line position, Fig. 1, back to its inoperative full line position.

From the foregoing it will be seen that the invention sets forth simple means by which a

thread cutter mounted on the lay can be operated at the time of a weft replenishing operation by means of an operator movable into registry with the slide carrier 50 of the thread cutting mechanism. The operator is moved along a guide which is parallel to the transfer stud 27 by movement of a member of the magazine, such as the rocking of shaft 16, when the member moves from its normal to transfer position. The arm 75, rod 71 and the lever 68 constitute operating connections between shaft 16 and the cutter operator 71, but the invention is not necessarily limited to these parts as means for conveying motion from shaft 16 to the operator. The slot 73 in the connector 71 permits lost motion whereby the shaft 16 can return to its normal position while the operator is still engaged with the slide 50. Thereafter, the spring 98 returns the lever 68 to its normal inoperative position as the lay recedes from front center subsequent to completion of replenishment of the shuttle S.

Having thus described the invention it will be seen that changes and modifications of the foregoing specific disclosure may be made without departing from the spirit and scope of the invention.

What is claimed as new is:

1. In control mechanism for a thread cutter on the lay of a weft replenishing loom having a reserve bobbin magazine, a member on the magazine which moves from the normal position thereof to transfer position before the lay reaches front center on a replenishing beat of the loom, an operator for the cutter movably mounted on the magazine and normally out of register with the thread cutter, and operative connections between said member and operator effective to move the latter into register with the thread cutter when the member moves from the normal position thereof to the transfer position thereof.

2. In control mechanism for a thread cutter on the lay of a weft replenishing loom provided with a reserve bobbin magazine having a stud for a transerrer arm, an elongated guide fixed with respect to said stud, an operator for the thread cutter slidable on said guide and normally out of register with the thread cutter, a member on the magazine which moves from the normal position thereof to transfer position before the lay reaches front center on a weft replenishing beat of the loom, and operative connections between said member and operator sliding the latter along said guide into register with the thread cutter when the member moves to the transfer position thereof.

3. In control mechanism for a thread cutter on the lay of a weft replenishing loom provided with a reserve bobbin magazine having a stud for a transerrer arm, an elongated cylindrical guide parallel to and spaced from and fixed with respect to said stud, an operator for the thread cutter slidable on said guide and having a part engaging the stud to prevent angular motion of the operator around the guide, said operator being normally out of register with said thread cutter, a member on the magazine which moves from the normal position thereof to transfer position before the lay reaches front center on a weft replenishing beat of the loom, and operative connections between said member and operator moving the latter along said guide into register with the thread cutter when said member moves to the transfer position thereof.

4. In control mechanism for a thread cutter

75 on the lay of a weft replenishing loom provided

with a reserve bobbin magazine having a stud for a transerrer arm, an elongated guide parallel to said stud, mounting means secured to the stud supporting said guide, an operator for the thread cutter slidable on said guide and normally out of register with the thread cutter, a lever pivoted on part of said mounting means and operatively connected to said operator, a member on the magazine which moves from the normal position thereof to transfer position before the lay reaches front center on a weft replenishing beat of the loom, and connections between said member and lever effective when the member moves to the transfer position thereof to cause the lever to slide the operator along said guide into register with the thread cutter.

5. In control mechanism for a thread cutter on the lay of a weft replenishing loom provided with a reserve bobbin magazine having a stud for a transerrer arm, an elongated guide parallel to said stud, mounting means secured to the stud supporting said guide, an operator for the thread cutter slidable on said guide and normally out of register with the thread cutter, a lever pivoted on part of said mounting means and operatively connected to said operator, resilient means supported by the mounting means operatively connected to the lever and normally holding the latter in normal position such as to locate the operator in normal position and out of register with the thread cutter, a member on the magazine which moves from the normal position thereof to transfer position before the lay reaches front center on a weft replenishing beat of the loom, and connections between said member and lever effective to rock the latter against the action of said resilient means and slide the operator

10

15

20

25

30

35

along said guide into register with the thread cutter, said resilient means thereafter returning the lever and operator to the normal positions thereof with the operator out of register with the thread cutter.

6. In control mechanism for a thread cutter on the lay of a weft replenishing loom provided with a reserve bobbin magazine, an operator for the thread cutter supported by and movable relatively to the magazine and being normally out of register with the thread cutter, a member on the magazine which moves from the normal position thereof to transfer position before the lay reaches front center on a weft replenishing beat of the loom and returns to normal position by the time the lay reaches front center on said replenishing beat of the loom, and means including a lost motion connection operatively connecting the member and operator effective to move the latter into register with the thread cutter when the member moves to the transfer position thereof, the operator due to said lost motion connection remaining in register and engagement with the thread cutter as the lay reaches front center and the member returns to the normal position thereof.
